METHOD OF MAKING VANE TRACKS

Walter Ferris, Milwaukee, Wis., assignor to The Oilgear Company, Milwaukee, Wis., a corporation of Wisconsin

Original application April 10, 1944, Serial No. 530,425. Divided and this application August 2, 1946, Serial No. 687,989

13 Claims. (Cl. 29—156.4)

1

This application is a division of application Serial No. 530,425, filed April 10, 1944.

The invention relates to a method of making vane tracks for vane type hydrodynamic machines.

The vane track of a hydrodynamic machine includes a plurality of abutments or bridges, with which the vanes coat to provide substantially liquid tight seals between the inlet and the outlet ports of the machine, and a plurality of track sections which are arranged between the bridges and form therewith a continuous track upon which the outer ends of the vanes ride during rotation of the rotor. The bridges are ordinarily arranged in pairs with one bridge of each pair arranged close to the periphery of the rotor and with the other bridge spaced from the periphery of the rotor when the machine is performing useful work, the bridge which is close to the rotor being called "sealing bridge" and the bridge which is spaced from the rotor being called the "pumping bridge" or the "working bridge." If all the bridges are stationary, the displacement of the machine is constant but the displacement may be varied by providing means to move the working bridge of each pair toward and from the rotor.

Vane type hydrodynamic machines are extensively used as pumps but a properly designed vane type hydrodynamic machine may function as a motor. When the machine is used as a pump, its rotor is ordinarily rotated at such a high speed that the centrifugal force is sufficient to keep the vanes in contact with the track and it is only necessary to hydrostatically balance the vanes. However, if the machine is operated at slow speeds, as by being used as a motor, the centrifugal force is insufficient to keep the vanes in contact with the track in which case the machine is provided with suitable means for positively moving the vanes outward such as means for supplying high pressure liquid to the inner ends of the outward moving vanes.

When the working bridges of a machine having two pairs of bridges are spaced from the rotor and the rotor is rotated, each vane will move inward as its outer end moves from a working bridge toward the adjacent sealing bridge, it will move outward as its outer end moves from the sealing bridge toward the next working bridge, it will move inward as its outer end moves from that bridge toward the next sealing bridge, and it will move outward as its outer end moves from that sealing bridge toward the first mentioned bridge. Each vane thus makes two reciprocations during each revolution of the rotor and, since the

2

rotor is often driven at very high speeds, the reciprocations may be very rapid.

If the track is so shaped that it forces each vane inward too rapidly, the vane will tend to dig into the track and thus cause excessive wear of the track or the vane or both. If the slope of the track at any point is so steep that an outward moving vane cannot follow it, the vane may leave the track at that point and reengage the track at another point with an impact that tends to damage both the track and the vane. Consequently, the shape of the track must be such as to provide gradual accelerations and decelerations of the vanes.

A track having a surface so shaped as to cause uniform accelerations and decelerations of the vane would provide an ideal condition which may be approached in a unitary rigid vane track for a constant displacement machine but in a variable displacement machine the contour of the track will vary as the movable bridges are moved inward and outward to vary the displacement.

The present invention has as an object to provide a method of making a vane track having extensible vane track sections which cooperate with bridges to form an endless track of variable length for guiding the vanes of a variable displacement hydrodynamic machine in their inward and outward movements, which track may be supported solely by the bridges and which cooperates with the bridges to form a vane track of a contour that will cause gradual accelerations and decelerations of the vanes in their radial movements.

Another object is to provide a method whereby such extensible vane track sections may be accurately and economically manufactured.

Other objects and advantages will appear from an explanation of the method and a description of a vane track section made according thereto as hereinafter set forth.

A vane track made according to the invention is illustrated in the accompanying drawings in which the views are as follows:

Fig. 1 is a transverse section through one half of a pump in which vane tracks constructed according to the invention are incorporated and which shows the pump adjusted to maximum displacement.

Fig. 2 is a transverse section through the opposite half of the pump and shows the pump adjusted to minimum displacement.

Fig. 3 is a view of the inner peripheral face of one of the track sections shown in Fig. 1 and

it includes portions of the bridges to which that section is connected.

Fig. 4 is an end or edge view showing the two parts of track section shown in Fig. 3 separated from each other.

Fig. 5 is a view of the outer sides of the track section parts shown in Fig. 4.

Fig. 6 is a transverse section taken on the line 6—6 of Fig. 5.

Fig. 7 is an edge or end view of an element from which the principal parts of the track sections shown in Fig. 1 are made.

Fig. 8 is an end or edge view of one section of the element shown in Fig. 7.

Fig. 9 is an outside view of the section shown in Fig. 8 and together with that figure illustrates how the section is divided into parts.

Fig. 10 is an edge view of an element from which the guide segment shown in Figs. 4—6 is made.

Fig. 11 is a diagram illustrating a method for determining the lengths of the radii of the track surfaces on the bridges and on the track sections of a hydrodynamic machine such as the pump shown in Figs. 1 and 2.

For the purpose of illustration, a vane track made according to the invention has been shown incorporated in a variable displacement nonreversible pump but it may as readily be incorporated in a reversible pump or in a motor.

The pump shown in Figs. 1 and 2 has a plurality of vanes 1 slidable in suitable slots formed radially in a cylindrical rotor 2 which is fixed upon a shaft 3 to be rotated thereby. The outer ends of vanes 1 engage an endless track upon which the vanes ride when the rotor is rotated. The vane track includes two diametrically opposed sealing bridges 4 and 5, which are fixed in stationary positions close to the periphery of rotor 2, two pumping bridges 6 and 7 which are spaced 90° from the other two bridges and are adapted to be moved toward and from the periphery of rotor 2 to vary pump displacement, and four extensible track sections 8 each of which is arranged between and connected to adjacent bridges. Bridge 7 has been shown arranged close to rotor 2 to illustrate the position of the parts when pump displacement is zero and bridge 6 is shown spaced from rotor 2 to illustrate the position of the parts when pump displacement is near maximum.

The rotor and the vane track are arranged between two cheek plates and within an annular spacer ring all of which is enclosed in a suitable casing. For example, the pump shown in Figs. 1 and 2 has its rotor and vane track arranged inside of an annular spacer ring 9 and between two cheek plates (not shown) which engage opposite sides of ring 9, and the entire assembly is enclosed within a casing 10.

The bridges are closely fitted between the cheek plates and in suitable recesses formed in the spacer ring, sealing bridges 4 and 5 being fixed in stationary positions while pumping bridges 6 and 7 are slidable in the recesses and adapted to be moved inward and outward by any suitable means to vary the displacement of the pump.

The space between the periphery of rotor 2 and the inner periphery of spacer ring 9 communicates with two interconnected diametrically opposed intake ports 11 and two interconnected diametrically opposed discharge ports 12 which are arranged adjacent to the periphery of the rotor. Each port is arranged between adjacent bridges, and liquid seals between adjacent ports

are provided by the bridges and the vanes in contact therewith.

Since vane type pumps are well known and since a typical pump of this type is illustrated and described in U. S. Patent No. 2,141,171 to which reference may be had for details of construction and mode of operation, further illustration or description of the pump is thought unnecessary, it being deemed sufficient to state that, when rotor 2 is rotated in the direction of the arrow and the pumping bridges are spaced from the rotor, the vanes will move progressively outward as the outer ends thereof move along the vane track from a sealing bridge to a pumping bridge and they will be forced inward by the track as the outer ends thereof move along the track from a pumping bridge to a sealing bridge. The spaces between the outer ends of the outward moving vanes will be filled with liquid from intake ports 11 and, as each vane crosses a pumping bridge, the liquid between it and the preceding vane will be discharged through a port 12.

If the track surface on each track section were of such a length that one of its ends would abut the ends of the track surface on the adjacent sealing bridge when pump displacement was zero and its other end would abut the track surface on the adjacent pumping bridge when pump displacement was maximum, one end or the other of the track surface on the track section would move away from the track surface on the adjacent bridge as the pumping bridge moved in one direction or the other so that there would at all times be a gap in the vane track at one or both ends of each track section.

In order that the track sections may be connected to the bridges and provide an unbroken path for the vanes, each stationary bridge has a portion 13 at opposite sides thereof reduced in thickness, each movable bridge has a portion 17 at opposite sides thereof reduced in thickness, each track section 8 has notches or recesses 18 and 19 formed in opposite ends thereof to receive reduced portions 16 and 17, and the matched end portions of each track section are provided with holes 20 and 21 to receive pins 22 and 23 by means of which each track section is pivotally connected to adjacent bridges, the notched portions of the track section overlapping the reduced portion of the bridges to provide an unbroken track surface as shown in Fig. 3.

Each track section 8 includes two principal parts 26 and 27, which have a circular T-shaped groove 28 formed therein and extending through the outer periphery thereof, and a circular T-shaped guide segment 29 which is fitted in groove 28. The inner peripheral faces of parts 26 and 27 are finished to the same radius to provide a smooth track surface for guiding the vanes and groove 28 is formed concentric with this track surface so that guide segment 29 may hold parts 26 and 27 in alinement with each other while permitting the two parts to move relatively to each other in a circumferential direction to vary the length of the vane track. The arrangement is such that each track section 8 is pivotally supported at both of its ends and it is self supporting intermediate its ends. Segment 29 is preferably fixed to one of the two parts, such as part 27, as by means of a pin 30.

The adjacent ends of parts 26 and 27 are so shaped as to provide an unbroken path for the vanes as they pass from one part to the other. For example, the inner end of part 26 may have two oppositely inclined faces 31 which converge

upon the centerline of the track and the inner end of part 27 may be provided with oppositely inclined faces 32 which diverge from the centerline of the track so that the end of part 27 is complementary to the adjacent end of part 26 as shown in Fig. 3. This arrangement provides a bearing for nearly the entire width of each vane while it passes from one to the other of the two parts of each section.

The vanes move radially when the pump is discharging liquid and the radial accelerations of the vanes must be maintained within certain limits in order that the outward moving vanes may remain in contact with the track and in order that the vanes being forced inward by the track may not bear so heavily against the track as to cause excessive friction and wear.

If the track surfaces of track sections 8 and bridges 4, 5, 6 and 7 were concentric with the rotor, the track would be substantially circular when the displacement of the pump was zero at which time the vanes would have substantially no radial movement but when the pump was adjusted to maximum displacement, at which time the radial movement of the vanes would be maximum, the track surface on each track section 8 would form an angle with the track surface on the adjacent bridge. The accelerations of the vanes riding upon the concave track surfaces may be maintained within the permissible limits but, as each vane passed across the angle at the junction of a track section surface and a pumping bridge surface, its radial movement would be suddenly reversed and hence uncontrolled at the very instant that it was performing a maximum amount of work. Also, since the bifurcated end of a track section overlaps the reduced portion on the adjacent bridge in order to provide an unbroken path for the vanes, the end of a track section would extend above the track surface of the sealing bridge to which it was connected and the end of that bridge would extend above the track surface of the same track section and thereby form obstructions in the path of the vanes when pump displacement was at or near maximum.

In order to prevent damage to either the track or the vane and to keep the accelerations of the vanes from being excessive, the bridges are provided with concave track surfaces having a suitable radius, the track sections are provided with concave track surfaces having preferably such a radius that the track surfaces of a track section and the adjacent pumping bridge will be tangent at their junction when pump displacement is maximum and the track surfaces of a track section and the adjacent sealing bridge will be nearly tangent at their junction when pump displacement is zero, pivot pins 22 and 23 are arranged as far radially outward as may be convenient within the available space, the concave surfaces on each track section and the adjacent sealing bridge are joined by a convex surface when pump displacement is maximum and the concave surfaces on each track section and the adjacent pumping bridge are joined by a convex surface when pump displacement is minimum so that the concave track surfaces on a track section and one adjacent bridge are joined by a smooth transition curve when the track surfaces on that section and the other adjacent bridge are tangent or nearly tangent. The radii of the track surfaces may be determined in a manner to be presently explained. The transition curve causes the vanes to move radially as they pass

over it but the curve is such that the accelerations and decelerations of the vanes at this point are well within the permissible limits. With this arrangement, the radial movement of a vane is very little when it is performing a maximum amount of work, that is, when pump displacement is maximum and the vane is passing across the pumping bridge.

The convex track surfaces may be formed upon the vane track sections but, for the purpose of illustration, they have been shown on the bridges and the ends of the track sections have been shown chamfered as indicated at 33 and 34 in Fig. 4 so that they will not extend above the track surfaces of the bridges.

The vane track may be accurately and economically made by the following method:

An annular element 35 of the approximate size of the complete vane track is so formed, as by casting, to include a plurality of unfinished track sections 8^a from which finished track section parts 26 and 27 may be made. Element 35 could include more than four unfinished track sections 8^a but, for the purpose of illustration, it has been shown in Fig. 7 as including four unfinished track sections 8^a and four separators 4^a, 5^a, 6^a and 7^a all of which are formed integral with each other and correspond, respectively, to the track sections 8 and the bridges 4, 5, 6 and 7 shown in Figs. 1 and 2.

The inner periphery of element 35 is ground or otherwise finished to provide a smooth track surface having a radius 36 which is ordinarily less than the radius of the rotor of the pump in which the track sections are to be used and is preferably determined by a method to be presently explained.

An annular groove is formed in the outer periphery of element 35 and it is made wide enough to accommodate the radial length of guide element 29 as shown in Fig. 6. The groove is extended inward until its inner wall has a radius 37 which is enough greater than radius 36 to provide a web of sufficient thickness between the groove and the track surfaces. The groove is then extended laterally between radius 37 and a greater radius 38 to provide spaces for the axial length of segment 29, thereby forming an annular T-shaped groove 28^a which corresponds to the groove 28 shown in Figs. 4-6. While holes 20 and 21 may be formed at any time, they are preferably formed by drilling through a template which may be readily adjusted upon element 35.

Element 35 is then cut at each end of each section 8^a to sever the four sections from the separators. Notches 18 and 19 are then formed in the ends of each section either by machining from the solid or by finishing to size openings which were provided in element 35 when it was formed.

The ends of each section 8^a are chamfered, as indicated at 33 and 34, and the section is cut into two parts 26 and 27 by two saw cuts 39 and 40 which preferably are normal to the chord of the section, as shown in Fig. 8, and extend inward from opposite sides of the section at an angle which is preferably about 45° as shown in Fig. 9.

The guide segments 29 are made from an annular element 41 (Fig. 10) which is T-shaped in cross-section and consists of a plurality of segments 29^a each of which corresponds to a guide segment 29. Element 41 is machined upon its inside to a radius 37^a, upon the outside of its flange to a radius 38^a and upon its sides to a width slightly less than the width of groove 28. Radii 37^a and 38^a vary in length from radii 37 and 38 just enough to enable the segments cut from element 41 to have a sliding fit in groove 28.

Element 41 is then divided into segments 29 by saw cuts 42 and the ends of the segments are beveled, as indicated at 43, either before or after the segments are cut apart.

One of the segments is then inserted into a track section 8 and fastened to one of the parts, such as part 27, by inserting a pin 30 into aligned holes formed in the segment and in the track section part.

The concave portion of the track surface on each bridge is preferably circular so that a plurality of bridges may be fastened to a fixture and the inner faces of all of those bridges first machined, as by boring, and then finished as by grinding to provide a smooth track surface on each bridge but it is not necessary that the concave track surface of each bridge be an exact circular arc. Each end of each bridge is rounded as by grinding or otherwise to form a convex surface which is concentric with the adjacent hole 20 or 21 and is tangent to the concave surface, the convex surfaces preferably being formed after the concave surface is finished.

A method for determining the radii of the track surface on the bridges and on the track sections of a hydrodynamic machine, such as the pump shown in Figs. 1 and 2, is illustrated in Fig. 11 in which a sealing bridge and one pumping bridge, such as bridges 5 and 7, are shown in the positions occupied when pump displacement is zero and the other pumping bridge, such as bridge 6 is shown in the position occupied when pump displacement is maximum.

As shown in Fig. 11, the concave surface on each bridge has a radius 51 which is slightly greater than the radius of the rotor but the radius may be and in practice sometimes is slightly less than the radius of the rotor. With the radius as shown and with pump displacement at zero, all of the concave surfaces on all of the bridges are concentric with but spaced slightly from the periphery of the rotor and their radius extends from a center C1 which is also the axis of the rotor. When a pumping bridge such as bridge 6 is in its maximum displacement position, the radius of its concave surface extends from a center C2 which is spaced from center C1 a distance which for convenience is called the stroke of the pump and is equal to the distance through which the bridge 6 moves from its zero displacement position to its maximum displacement position.

The concave track surface of each bridge extends from one to the other of its two radii that pass through the pivot pins in that bridge. As shown, the concave surface 52 of bridge 5 extends from radius 51a to radius 51b and the concave surface on 53 on each of bridges 6 and 7 extends from radius 51c to radius 51d.

The convex track surface on each end of each bridge is concentric with the adjacent pivot pin and tangent to the concave surface at the radius which passes through that pin. For example, each sealing bridge, such as bridge 5, has at each end thereof a convex track surface 54 which is tangent to surface 52 at radius 51a or 51b and has a radius 55 which is struck from the center of the adjacent pin 22, and each pumping bridge, such as bridge 6, has at each end thereof a convex track surface 56 which is tangent to concave surface 53 at radius 51c or 51d and has a radius 57 which is struck from the center of the adjacent pin 23.

In order that a track section may have one end of its track surface tangent to the concave surface on the adjacent pumping bridge when

pump displacement is maximum, the track surface on the track section has the center of its arc located at a point on the radius which extends from center C2 through the adjacent pin 5 in the pumping bridge and, in order that the other end of the track section surface may be tangent to the track surface on the sealing bridge, the center point is located on that radius equidistant from the concave surface on the pumping bridge and a point on the adjacent convex surface on the sealing bridge.

As shown, the track surface of track section 8 has a radius 36 struck from a center C3 which is located on radius 51c equidistant from concave surface 53 and the point nearest to center C3 on the adjacent convex surface 54 so that the track surface of track section 8 is tangent to surface 53 at radius 51c and is tangent to convex surface 54 at a radius 36a which extends from center C3 through the adjacent pivot pin 22.

The arrangement is such that the vanes have practically no change in rate of radial movement as they travel from one track section 8 on to surface 53 and from surface 53 on to the next track section 8 at which time the vanes are performing the maximum amount of work. The vanes travelling from a surface 52 to and along a track section 8 will move radially outward and the vanes travelling along and from a track section 8 to a surface 52 will move radially inward and the radially moving vanes will continue to move radially in the same direction while passing across a convex surface 54 but at that time the vanes are performing little or no work and the radial accelerations and decelerations of the vanes may be readily determined and are well within the permissible limits. These accelerations and decelerations may be further reduced by moving pins 22 and 23 farther outward.

When the pumping bridges are moved inward to reduce pump displacement, centers C2 and C3 will move inward with them, track sections 8 will pivot upon pins 22 and 23 and the track section parts will telescope with each other to shorten the length of the track. When the pumping bridges are moved to their zero displacement position, center C2 will coincide with center C1 and center C3 will move close to center C1 as indicated by center C3a which is the center of the arc on the track section 8 which is arranged between bridges 5 and 7.

As the pumping bridges move inward, one end of the concave track surface on each track section 8 moves toward concave track surface 52 to reduce the length of the convex transition curve between the two concave curves, and the other end of the concave track section surface moves very slowly out of tangency with the adjacent surface 53 and into tangency with the convex surface 56 which then provides a small convex transition curve between the concave curves but the transition curve on surface 56 is so short even at zero displacement as to be substantially negligible. That is, the length of the convex transition curve between concave surface 53 and the adjacent concave track section surface is the distance between radius 51c and the radius 36b which extends from center C3a through the adjacent pivot 23 and the length of the convex transition curve between concave surface 52 and the adjacent concave track section surface is the distance between the radius 51b and the radius 36c which extends from center C3a through the adjacent pivot pin 22. Since at zero

displacement the distances between radius 51^c and radius 36^b and between radius 51^b and radius 36^c are substantially negligible, the vane track is substantially circular when pump displacement is zero except for the fact that track radius 36^c is zero except for the fact that track radius 36^c has been made smaller than bridge radius 51^b to produce the tangent conditions of adjacent concave and convex arcs just described. This shortened track radius 36^c causes a very slight radial movement of each vane which has no significance because the vane is unloaded at this time.

The invention thus provides a method of accurately and economically making vane tracks which cause the vanes in contact therewith to gradually accelerate and decelerate as they move radially in the rotor.

The method described herein may be varied to some extent without departing from the scope of the invention which is hereby claimed as follows:

1. The method of making adjustable vane track sections for a hydrodynamic machine having a rotor and an endless vane track arranged around said rotor and including alternate track sections and bridges and being adjustable to vary its length and thereby vary the displacement of said machine, said method comprising the steps of forming an annular member which is of the general shape and size of said track and has a plurality of sections corresponding to the adjustable sections of said vane track, finishing the inner periphery of said member to provide a smooth circular track surface, forming in said member at least one annular groove which is spaced from said track surface and has radially opposed bearing faces, cutting said member into pieces to separate said sections, providing a connection at each end of each section for pivotally connecting the sections to said bridges, cutting each section diagonally to divide it into two parts and to provide an unbroken path for the vanes passing from one part to the other, forming a plurality of guide segments which are complementary to the grooves in said parts, and inserting a segment in each of said grooves to hold the two parts of each track section in alignment while permitting the section to be extended or contracted.

2. The method of making adjustable vane track sections for a vane type hydrodynamic machine having four bridges spaced about 90° apart and track sections arranged between said bridges and forming therewith an endless vane track, at least two diametrically opposed bridges being adjustable to vary the length of said track, said method comprising the steps of forming an annular member of the general shape of said vane track, finishing the inner periphery of said member to provide a smooth circular track surface, forming in said member at least one annular groove which is spaced from said track surface and has radially opposed bearing faces, cutting said member into eight pieces four of which are semi-finished track sections, providing a connection at each end of each section for pivotally connecting the sections to said bridges, separating each section into two parts by making two oppositely inclined cuts which extend from opposite sides of the section inward far enough to separate the two parts, making a plurality of guide segments which are complementary to the grooves in said parts, inserting a segment in each of said grooves to hold the two parts of each track section in alignment while permitting the section to be extended or

contracted, and fastening said segment to one of said parts.

3. The method of making adjustable vane track sections for a hydrodynamic machine having a rotor and an endless vane track arranged around said rotor and including alternate track sections and bridges and being adjustable to vary its length and thereby vary the displacement of said machine, said method comprising the steps of forming an annular member which is of the general shape and size of said track and has a plurality of sections corresponding to the adjustable sections of said vane track, finishing the inner periphery of said member to provide a smooth circular track surface, forming in said member at least one annular groove which is spaced from said track surface and has radially opposed bearing faces, cutting said member into pieces to separate said sections, providing a connection at each end of each section for pivotally connecting the sections to said bridges, cutting each section diagonally to divide it into two parts and to provide an unbroken path for the vanes passing from one part to the other, forming a ring which is complementary to the groove in said member, cutting said ring into segments, and inserting a segment into each of said grooves to hold the two parts of each section in alignment while permitting the section to be extended or contracted.

4. The method of making adjustable vane track sections for a hydrodynamic machine having a rotor and an endless vane track arranged around said rotor and including alternate track sections and bridges and being adjustable to vary its length and thereby vary the displacement of said machine, said method comprising the steps of forming an annular member which is of the general shape and size of said track and has a plurality of sections corresponding to the adjustable sections of said vane track, finishing the inner periphery of said member to a radius less than the radius of said rotor to provide a smooth circular track surface, forming in said member at least one annular groove which is concentric with said track surface and has radially opposed bearing faces, cutting said member into pieces to separate said sections, providing a connection at each end of each section for pivotally connecting the sections to said bridges, cutting each section diagonally to divide it into two parts and to provide an unbroken path for the vanes passing from one part to the other, making a plurality of guide segments which are complementary to the grooves in said parts, and inserting a segment in each of said grooves to hold the two parts of each track section in alignment while permitting the section to be extended or contracted.

5. The method of making adjustable vane track sections for a hydrodynamic machine having a rotor and an endless vane track arranged around said rotor and including alternate track sections and bridges and being adjustable to vary its length and thereby vary the displacement of said machine, said method comprising the steps of forming an annular member which is of the general shape and size of said track and has a plurality of sections corresponding to the adjustable sections of said vane track, finishing the inner periphery of said member to provide a smooth circular track surface, cutting into said member from the outside thereof an annular groove which is T shaped in cross-section, cutting said member into pieces to separate said sections, providing a connection at each end of each section

for pivotally connecting the sections to said bridges, cutting each section diagonally to divide it into two parts and to provide an unbroken path for the vanes passing from one part to the other, making a guide segment which is complementary to the T-shaped groove in a track section, and inserting said segment into the T-shaped grooves in the two halves of a track section.

6. The method of making adjustable vane track sections for a vane type hydrodynamic machine having four bridges spaced about 90° apart and track sections arranged between said bridges and forming therewith an endless vane track, at least two diametrically opposed bridges being adjustable to vary the length of said track, said method comprising the steps of forming an annular member of the general shape of said vane track, finishing the inner periphery of said member to provide a smooth circular track surface, cutting into said member from the outside thereof an annular groove which is T-shaped in cross-section, cutting said member into eight pieces four of which are semi-finished track sections, providing a connection at each end of each section for pivotally connecting the sections to said bridges, separating each section into two parts by means of cuts which extend diagonally inward from opposite sides of the section and meet each other, forming a ring which is complementary to the T-shaped groove in said member, cutting said ring into segments, and inserting one of said segments into the T-shaped groove in a track section to prevent radial displacement of one half-section relative to the other half-section.

7. The method of making adjustable vane track sections for a hydrodynamic machine having a rotor and an endless vane track arranged around said rotor and including alternate track sections and bridges and being adjustable to vary its length and thereby vary the displacement of said machine, said method comprising the steps of casting from iron an annular member which is of the general shape and size of said track and has a plurality of sections corresponding to the adjustable sections of said vane track, machining said member upon both sides thereof to finish it to a predetermined width, adjusting said member on a machine, boring said member to a predetermined radius to form a track surface upon the inner periphery thereof, forming in said member without altering the adjustment thereof at least one annular groove which is spaced from said track surface and has radially opposed bearing faces, grinding said track surfaces, boring through a template attached to said member holes in the ends of said sections for pivot pins to connect said sections to said bridges, cutting said member into pieces to separate said sections, cutting each section diagonally to divide it into two parts and to provide an unbroken path for the vanes passing from one part to the other, making a plurality of guide segments which are complementary to the grooves in said parts, and inserting a segment in each of said grooves to hold the two parts of each track section in alignment while permitting the section to be extended or contracted.

8. The method of making an adjustable vane track to extend around the rotor of a hydrodynamic machine and to include alternate bridges and track sections, comprising the steps of forming a concave track surface upon the inner face of a plurality of bridges, forming a convex surface at each end of the concave surface on each of the bridges, forming a pin hole in each side

of each bridge, forming a plurality of unfinished track sections, finishing the inner face of each track section to provide a smooth concave track surface, forming in each section at least one groove which is concentric with and spaced from the track surface thereon and which has radially opposed bearing faces, forming a pin hole in each end of each section for pivotally connecting the sections to said bridges, cutting each section diagonally to divide it into two parts and to provide an unbroken path for the vanes passing from one part to the other, making a plurality of guide segments which are complementary to the grooves in said parts, inserting a segment into the grooves in said parts to hold the two parts of each section in alignment while permitting the section to be varied in length, arranging a plurality of said sections and an equal number of bridges alternately around a common center, and pivotally connecting opposite ends of each of those track sections to the adjacent bridges by inserting pins in the pin holes formed therein.

9. The method of making an adjustable vane track to extend around the rotor of a hydrodynamic machine and to include alternate bridges and track sections, comprising the steps of arranging a plurality of unfinished bridges in fixed positions equidistant from a common center, forming concave track surfaces upon the inner faces of all of said bridges simultaneously, forming a pin hole in each side of each bridge, forming at each end of the concave surface on each of the bridges a convex surface which is tangent to the concave surface and is concentric with the adjacent pin hole, forming a plurality of unfinished track sections, finishing the inner face of each track section to provide a smooth concave track surface, forming in each section at least one groove which is concentric with and spaced from the track surface thereon and which has radially opposed bearing faces, forming a pin hole in each end of each section for pivotally connecting the sections to said bridges, cutting each section diagonally to divide it into two parts and to provide an unbroken path for the vanes passing from one part to the other, making a plurality of guide segments which are complementary to the grooves in said parts, inserting a segment into the grooves in said parts to hold the two parts of each section in alignment while permitting the section to be varied in length, arranging a plurality of said sections and an equal number of bridges alternately around a common center, and pivotally connecting opposite ends of each of those track sections to the adjacent bridges by inserting pins in the pin holes formed therein.

10. The method of making an adjustable vane track to extend around the rotor of a hydrodynamic machine and to include alternate bridges and track sections, comprising the steps of forming a concave track surface upon the inner face of a plurality of bridges, forming a convex surface at each end of the concave surface on each of the bridges, providing at each side of each bridge a connection for a track section, forming an annular member having a plurality of integral sections which correspond to said track sections, finishing the inner periphery of said member to provide a smooth circular track surface, forming in said member at least one annular groove which is spaced from said track surface and has radially opposed bearing faces, cutting said member into pieces to separate said sections,

13

providing a connection at each end of each section for pivotally connecting the sections to said bridges, cutting each section diagonally to divide it into two parts and to provide an unbroken path for the vanes passing from one part to the other, making a plurality of guide segments which are complementary to the grooves in said parts, inserting a segment into the grooves in said parts to hold the two parts of each section in alignment while permitting the section to be varied in length, arranging a plurality of said sections and an equal number of bridges alternately around a common center, and pivotally connecting opposite ends of each of those track sections to the adjacent bridges.

11. The method of making an adjustable vane track to extend around the rotor of a hydrodynamic machine and to include alternate bridges and track sections, comprising the steps of forming a concave track surface upon the inner face of a plurality of bridges, forming a pin hole in each side of each bridge, forming at each end of the concave surface on each of the bridges a convex surface which is tangent to the concave surface and is concentric with the adjacent pin hole, forming an annular member having a plurality of integral sections which correspond to said track sections, finishing the inner periphery of said member to provide a smooth circular track surface, forming in said member at least one annular groove which is spaced from said track surface and has radially opposed bearing faces, cutting said member into pieces to separate said sections, forming a pin hole in each end of each section for pivotally connecting the sections to said bridges, cutting each section diagonally to divide it into two parts and to provide an unbroken path for the vanes passing from one part to the other, making a plurality of guide segments which are complementary to the grooves in said parts, inserting a segment into the grooves in said parts to hold the two parts of each section in alignment while permitting the section to be varied in length, arranging a plurality of said sections and an equal number of bridges alternately around a common center, and pivotally connecting opposite ends of each of those track sections to the adjacent bridges by inserting pins in the pin holes formed therein.

12. The method of making an adjustable vane track to extend around the rotor of a hydrodynamic machine and to include alternate bridges and track sections, comprising the steps of arranging a plurality of unfinished bridges in fixed positions equi-distant from a common center, forming concave track surfaces upon the inner faces of all of said bridges simultaneously, forming a convex surface at each end of the concave surface on each of the bridges, providing at each side of each bridge a connection for a track section, forming an annular member having a plurality of integral sections which correspond to said track sections, finishing the inner periphery of said member to provide a smooth circular track surface, forming in said member at least one annular groove which is spaced from

14

said track surface and has radially opposed bearing faces, cutting said member into pieces to separate said sections, providing a connection at each end of each section for pivotally connecting the sections to said bridges, cutting each section diagonally to divide it into two parts and to provide an unbroken path for the vanes passing from one part to the other, making a plurality of guide segments which are complementary to the grooves in said parts, inserting a segment into the grooves in said parts to hold the two parts of each section in alignment while permitting the section to be varied in length, arranging a plurality of said sections and an equal number of bridges alternately around a common center, and pivotally connecting opposite ends of each of those track sections to the adjacent bridges.

13. The method of making an adjustable vane track to extend around the rotor of a hydrodynamic machine and to include alternate bridges and track sections, comprising the steps of arranging a plurality of unfinished bridges in fixed positions equi-distant from a common center, forming concave track surfaces upon the inner faces of all of said bridges simultaneously, forming a pin hole in each side of each bridge, forming at each end of the concave surface on each of the bridges a convex surface which is tangent to the concave surface and is concentric with the adjacent pin hole, forming an annular member having a plurality of integral sections which correspond to said track sections, finishing the inner periphery of said member to provide a smooth circular track surface, forming in said member at least one annular groove which is spaced from said track surface and has radially opposed bearing faces, cutting said member into pieces to separate said sections, forming a pin hole in each end of each section for pivotally connecting the sections to said bridges, cutting each section diagonally to divide it into two parts and to provide an unbroken path for the vanes passing from one part to the other, making a plurality of guide segments which are complementary to the grooves in said parts, inserting a segment into the grooves in said parts to hold the two parts of each section in alignment while permitting the section to be varied in length, arranging a plurality of said sections and an equal number of bridges alternately around a common center, and pivotally connecting opposite ends of each of those track sections to the adjacent bridges by inserting pins in the pin holes formed therein.
